UNITED STATES PATENT OFFICE.

ROBERT C. FUNKE, OF PHILADELPHIA, PENNSYLVANIA.

HAMMOCK.

SPECIFICATION forming part of Letters Patent No. 627,994, dated July 4, 1899.

Application filed November 16, 1898. Serial No. 696,539. (No model.)

To all whom it may concern:

Be it known that I, ROBERT C. FUNKE, a citizen of the United States, residing at the city of Philadelphia, in the county of Philadelphia and State of Pennsylvania, have invented certain new and useful Improvements in Hammocks, of which the following is a specification.

The object of my invention is to provide comparatively inexpensive, strong, durable, and sightly means for connecting a hammock body or bed with the loops of its suspension-cord and also, when desirable, with a stretcher or spreader.

To this end my invention comprises the improvements hereinafter described and claimed.

The nature, characteristic features, and scope of my invention will be more fully understood from the following description, taken in connection with the accompanying drawings, forming part hereof, and in which—

Figure 1 is a perspective view illustrating a hammock embodying features of my invention. Fig. 2 is a detail view drawn to an enlarged scale and illustrating a portion of the head end of the hammock. Figs. 3, 4, and 5 are views respectively illustrating stages in the manufacture of a hammock embodying features of my invention; and Figs. 6 and 7 are, respectively, views of opposite sides of a portion of the hammock that is illustrated at the foot end thereof in Fig. 1.

In the drawings are shown a series of loops 1, formed by the suspension-cord. These loops may be made by tying the suspension-cord to the ring or device 2 in such manner that it is repeatedly carried outward and back, thus forming the loops 1. The hammock body or bed 3 may be hemmed at its ends, and the ends are split so as to form a series of tabs 4, Fig. 3. Each tab 4 may then be hemmed along its edges, as shown by dotted lines in Fig. 4. Each tab is inserted 45 through the bight of a loop 1, as shown in Fig. 5, and the edges of the tab are doubled over the cords of the loop and sewed to place, as indicated by dotted lines at 5, Fig. 6, so that in the complete structure the tab is surrounded by the bight 6, Fig. 7, of the loop and the respective cords of the loop pass through tubular openings in the tab formed by folding over and sewing down the edges of the same. Such a union or connection is neat 55 in appearance, durable in use, and easy to

manufacture. In this connection the fact that the loops are formed in the suspension-cord is obviously advantageous in that it effects a saving of time in rigging the hammocks.

Where a stretcher or spreader 7 is employed, it may be held to place by taking a turn around it with the loops, as shown at 8 in Fig. 2, and at the ends the spreader may be provided with a ring, through which one 65 of the tabs passes. When the hammock is loaded, the suspension-cords operate to draw the tabs and stretcher into firm contact with each other, so that slipping is obviated and the stretcher is retained to place.

It will be obvious to those skilled in the art to which my invention appertains that modifications may be made in details without departing from the spirit thereof. Hence I do not limit myself to the precise construction 75 and arrangement of parts hereinabove set forth, and illustrated in the accompanying drawings; but,

Having thus described the nature and objects of my invention, what I claim as new, 80 and desire to secure by Letters Patent, is—

1. The combination of loops formed in the suspension-cord, and tabs projecting from the bed and passing through the loops and having their side edges folded and attached to 85 form tubular openings through which the respective cords of the loop pass, substantially as described.

2. In combination loops formed in the suspension-cord, and a hammock-bed provided 90 at its ends with laterally-hemmed tabs which pass through the loops and have their side portions folded over the cords of the loops and sewed in the direction of the length of the hammock, substantially as described. 95

3. The combination of loops formed in the suspension-cord, tabs projecting from the bed and passing through the loops and having their side edges folded and attached to form tubular openings through which the respective cords of the loop pass, and a stretcher or spreader secured to place by a turn around it of the cords of each loop substantially as described. 100

In testimony whereof I have hereunto 105 signed my name.

ROBERT C. FUNKE.

In presence of—

W. J. JACKSON,
K. M. GILLIGAN.
